UNITED STATES PATENT OFFICE.

DANA E. HARDING, OF ARLINGTON, MASSACHUSETTS, ASSIGNOR TO HARDING ENGINEERING COMPANY, OF EAST BOSTON, MASSACHUSETTS, A CORPORATION OF MASSACHUSETTS.

CHECKING MACHINE.

Application filed May 13, 1925. Serial No. 30,031.

My present invention relates to leather working machines, and more particularly to an improved checking machine.

Heretofore that operation on hides or skins, known as checking, has been performed in a checking machine and in which machine it is necessary that the hide or skin be held by main force against the thrust exerted by the knife or knives. Such operation, therefore, has been both exceedingly laborious and exceedingly dangerous, as the amount taken off the hide or skin had to be gauged by the workman, was irregular, and uneven, and the hide often torn, the product resulting therefrom being very uneven in character.

With a view to overcoming objections to prior machines of this type and to dispense with, as far as possible, manual holding engag- 20 gaging of the hide or skin I have devised the subject matter of the present invention wherein an improved checking machine is provided with hide or skin holding mechanism and in which the thickness of the hide 25 or skin to be present in the finished product is automatically gauged.

The principal object, therefore, of my invention is an improved checking machine.

Another object of my invention is an im- 30 proved means for holding a hide or skin during the checking operation.

A further object of my invention is an improved cutting knife and method of mounting the same applicable to leather 35 working machines, together with safety devices protecting the operator.

Other objects and novel features of the construction and arrangement of parts comprising my invention will be apparent as the 40 description of the invention progresses.

In the accompanying drawings illustrating the preferred embodiment of my invention,

Fig. 1 is a front elevation;

Fig. 2 is a side elevation;

Fig. 3 is a fragmentary detail plan view showing the cutting knife reciprocating means;

Fig. 4 is a sectional elevation on the line 50 4-4 of Fig. 1 and with the hide holding or clamping means in holding position;

Fig. 5 is a fragmentary sectional detail of a portion of Fig. 4 showing the hide holding means in open position, and

Fig. 6 is a sectional elevation on the line 55 6-6 of Fig. 3.

Referring to the drawings, 10 and 11 des- 60 ignate right and left end members respec- 65 tively spaced apart from, and held in fixed position by, longitudinal members 12 ad- 70 jacent to the lower ends thereof. These 75 members 12 are secured to the end members 10 and 11 by bolts or rivets 13. Secured to the 80 upper rear ends of the end members 10 and 11 by bolts or rivets 14 is a longitudi- 85 nally extending member 15. Secured to the 90 upper surface of the members 10 and 11 and in alignment with each other are bearings 16 and in these bearings is rotatably mounted a shaft 17. Secured to the outer face of 95 the rectangular member 11 by bolts 18 is a bearing strut 19 in which is formed a bear- 100 ing 20 that is in alignment with the bear- 105 ings 16. Rotatably mounted in the bearing 20 is a shaft 21, and connecting the shafts 17 and 21 is a one revolution clutch 22, an annular groove 23 being formed in such member. Secured to the member 19 and extending in- 110 wardly toward the rectangular member 11 is a shaft 24 and rotatably mounted on the 115 shaft 24 is a pinion 25 that meshes with, and drives, a gear 26 secured to the shaft 21 by pin 27. Secured to the pinion 25 is a gear 120 28 which meshes with, and is driven by, a pinion 29 secured to a shaft 30 that is ro- 125 tatably mounted in a bearing in the member 19 and in a bearing member 31 secured to, or formed integral with, the rectangular 130 member 11. Mounted on the shaft 30 are the fast and loose pulleys 32 and 33 re- 135 spectively and over which may run belts 140 extending from any suitable source of power.

Rotatably mounted in the rectangular 145 members 10 and 11 adjacent to the bottom 95 thereof is a shaft 34 and on this shaft is se- 150 cured a treadle 35 and by means of which the shaft 34 may be oscillated. Adjacent 155 to the rectangular member 11 and on the shaft 34 is secured an inwardly extending 160 arm 36 and to the inner end of this arm is pivotally attached the lower end of a link 37. The upper end of the link 37 is pivot- 165 ally attached to the free end of a member 38 pivotally mounted on a shaft 138 secured 170 to a member 39 on the end member 11. Formed on the side face of the member 38 175 and extending laterally outward therefrom

is a lug 40. This lug is perforated to allow free passage of a threaded bolt 41, nuts 42 being threaded on such bolt for adjustment purposes as will be hereinafter described. 5 The upper end of this bolt 41 is pivotally attached to one arm 43 of a bell crank lever that is pivotally mounted in a bearing 44 formed on the member 11. The other arm, 45, of this bell crank lever is forked to fit 10 into the annular groove 23 in the clutch 22, the ends of the forks being provided with rollers 46 to lessen the friction therebetween. When the treadle 35 is operated, the free end of the arm 36 moves upward, causing the 15 lug 40 on the member 38 to move into engagement with the upper pair of nuts 42, thereby moving the forked ends of the arm 45 to the left, as viewed in Fig. 1, and causing the clutch member 22 to be operated 20 in a manner to connect the shafts 21 and 17. The clutch 22 is, or may be, any of the well known forms of one revolution clutches, and the details of such clutch will not, therefore, be described. 25 Secured to the shaft 17 between the rectangular members 10 and 11 is a sector 47, this sector including a portion of a cylinder, and opposite thereto a locking depression 48 for a purpose to be hereinafter described. 30 Secured to each end of the sector 47 by bolts or rivets 49 are members 50. Formed integral with each member 50 and extending radially outward from the shaft 17 is an arm 51 and to the outer end of this arm is 35 pivotally mounted, intermediate its ends, a lever 52. Extending between the levers 52 and secured thereto at each end thereof by bolts 53 is a locking bar 54 which cooperates with the locking groove 48 to lock or retain 40 a hide or skin in position on the sector. Also formed integral with the members 50 and extending radially outward from the shaft 17 are members 55. Pivots mounted in each of the members 55 is a lever 56. 45 To one end of the lever 56 is pivotally attached a member or link 57, this member being provided with a reduced end 58. This reduced end is threaded to receive an adjusting nut 59 and a member 60, the member 60 being pivotally attached to the lever 52. 50 The member 57 and the lever 56 at their point of connection are provided with cooperating faces 61 and 62 which, as will be seen from an inspection of Fig. 4, prevents 55 too far a movement of the joining point beyond a straight line joining the pivotal mounting of the lever 56 and the pivotal connection of the member 60 with the lever 52. Secured to the shaft 34 is a rearwardly 60 extending arm 63 equal in length to the rearwardly extending arm 36. Pivots secured to the free end of the arm 63 is a curved link 64, the purpose of the curvature in said link being to clear a conveying belt to be hereinafter described. Pivotally

attached to the upper end of the link 64 is a lever 65 similar in all respects to the lever 38 above described as being pivotally connected to the link 37. This lever 65 is rotatably mounted on a shaft 66 secured in a bearing member 67 formed integral with, or attached to, the end member 10. Rotatably mounted on the free end of each of the levers 56 is a roller 68 and these rollers engage with semi-circular cam members 69 secured to the end members 10 and 11 by bolts or rivets 70. Referring to Fig. 4, which shows the sector 47 having a hide 71 securely held in position thereon by means of the clamp bar 54, it will be obvious that, with the roller 68 at each end of the sector engaging with the inner surface of the cam member 69, it will be impossible for the clamp bar 54 to move from its locking position. If the sector 47 is rotating in the direction of the arrow shown in Fig. 4, it will be evident that, when the roller 68 clears the upper end of the cam member 69, the clamp members 54 can be moved away from the locking groove 48 if a way is found to break the toggle 90 joint between the member 47 and the lever 56. To accomplish this, I have secured at the upper end of each of the end members 10 and 11 brackets 72 in the upper end of each of which is a rearwardly extending bolt 95 73. Formed integral with each of the levers 56 is a lug 74 which, in the rotative movement of the sector, 47, is brought into engagement with the end of the bolt 73. The sector 47 rotating in the direction of the arrow shown in Fig. 4, it will be obvious that the engagement of the lugs 74 with the bolt 73 will cause a rotative movement of the lever 56 about its pivotal connection with the member 55, breaking the toggle between the member 57 and the lever 56 and moving the levers and links 52, 57, and 56 from the position shown in Fig. 4 to the position shown in Fig. 5, and in moving into this position, it will be obvious that the clamp bar 54 is moved out of the clamping groove 48 in the sector 47 and allowing the hide or skin 71 to slide off the sector 47 by gravity. Referring to Fig. 5, it will be noted that the roller 68 is now in such a position that, if the sector 47 were to be rotated in the direction of the arrow shown, such roller 68 would ride on the outside surface of the cam member 69. To accomplish this, I have secured to the right hand end of the shaft 17 a grooved pulley 75 and to this pulley attach one end of a flexible cord 76. In order to clear the conveying mechanism above referred to and to be hereinafter described, I lead the flexible cord 76 over a grooved pulley 77 that is rotatably mounted on a shaft 78 secured to the end member 10, and to the lower end of this flexible cord 76 attach a suitable weight 79. The weight 79 causes a rotative movement of the pulley 75 and a corresponding rota- 110 115 120 125 130

- tion of the shaft 17 and sector 47 in the direction of the arrow shown in Fig. 5, bringing the system of levers above referred to from the position shown in Fig. 5 into the 5 position shown in Fig. 2. When in the position shown in Fig. 2, each of the rollers 68 moves into engagement with pockets 80 formed on the levers 38 and 65. The lower end of each of the cam members 69 is provided with bevelled faces 81 and 82, the faces 81 moving the rollers 68 upward and to the right, as viewed in Figs. 2 and 4, and the faces 82 allowing a movement upward and to the left, as viewed in said figures. When, 10 therefore, the treadle 35 is operated, the links 37 are moved upwardly and the pockets 80 in the levers 38 and 65 rotate the levers 56, moving the rollers 68 along the faces 81 and into position to engage with the faces 82.
- 20 As above described, and simultaneously with the upward movement of the rollers 68, the clutch 22 is operated to cause a rotative movement of the shaft 17 and attached parts in the direction of the arrow shown in Figs. 2 and 4. During the upward movement of the rollers 68, the system of levers above described is moved from the position shown in Fig. 2 relative to the sector 47 and into the position shown in Fig. 4, it being understood, 25 of course, that, prior to the operation of the treadle 35, a hide or skin 71 has been placed on the sector 47 as shown in dotted lines in Fig. 2, so that, when the system of levers is moved as above described, the hide or skin 30 71 is firmly clamped to the sector 47.
- Secured to the longitudinally extending member 15 are brackets 83, and secured to the top of the brackets and extending parallel to the member 15 is a bevelled guide 84. 35 Slidably mounted on the bevelled guide 84, with provision for adjustment, is a slide 85. Adjustably mounted on the top of the slide 85 by means of bolts 86 is a knife holder 87. Formed integral with the slide 85 is a lug 40 88 and rotatably mounted in this lug is an adjusting screw 89 which engages with the knife holder 87. The screw 89 is provided with a knurled head 90 and by means of which the screw may be rotated and this 45 head is provided with a series of graduations cooperating with the indicating mark on the lug 88 and by means of which the inward and outward movement of the knife holder 87 may be measured. On the front face of 50 the knife holder 87 is mounted for vertical movement therein a knife 91, screws 92 being provided for moving said knife downwardly with respect to the holder. The cutting edge of such knife lies adjacent to the path of 55 movement of the surface of the sector 47, as clearly shown in Fig. 4, and by means of the screws 92, 86, and 90 the position of the knife edge with respect to said sector may be accurately adjusted. On one end of the slide 60 85 are formed lugs 93 and mounted in said lugs is a shaft 94 on which is rotatably mounted one end of a connecting rod 95. Secured to the longitudinally extending member 15 and the rectangular end member 11 is a member 96, and rotatably mounted in 65 suitable bearings formed in said member is a shaft 97. Secured to said shaft by pin 98 is an eccentric 99 which engages with an eccentric strap 100 formed on the connecting rod 95. Secured to the shaft 97 by pin 101 is 70 a bevelled pinion 102 which meshes with, and is driven by, a bevelled pinion 103 secured by pin 104 to the upper end of a shaft 105 that is rotatably mounted in suitable bearings 106 formed on the member 96. Secured to the lower end of the shaft 105 by pin 107 is a bevelled pinion 108 which meshes with, and is driven by, a bevelled gear 109 secured to the inner end of the shaft 30 by pin 110. 75
- Secured to the end of the shaft 97 remote from the bevelled pinion 102 is a sprocket 111 which is in alignment with a sprocket 112 secured to a shaft 113. This shaft 113 is rotatably mounted in suitable bearings 114 80 secured to the under surface of the members 12. Over the sprockets 111 and 112 runs a chain 115 and by means of which rotary movement is imparted to the shaft 113 from the shaft 97. Secured to the shaft 113 is a 85 roller pulley 116 and over this pulley runs a conveying belt 117, the belt acting to move the hides or skins 71 that may fall thereon upward and to the right of the machine, as viewed in Fig. 1. In order to prevent sagging of the upper reach of the conveyor belt 117 I provide a second roller pulley 118 that is secured to a shaft 119 rotatably mounted in bearings formed directly in the members 12. It is to clear this conveyor belt 117 that 90 the link 64 above described was made curved. 100
- Extending forwardly and downwardly from the brackets 83 are arms 120 and in each of these arms is secured an inwardly extending shaft 121. Rotatably mounted on the 105 shaft is a bar 122 that extends parallel to the knife 91 and in this bar is a guide blade 123, the upper edge of the guide blade lying parallel to, but below, the cutting blade 91, the object of this guide blade being to guide the 110 leather into position against the cutting edge of the knife 91. 115
- The operation of my improved machine is as follows, it being assumed that the parts have been assembled as above described and that the mechanism is in the position shown in Figs. 1 and 2. The operator, standing in front of the machine, takes a hide or skin off a pile, which is usually arranged at his left side, and passes it over the sector 47 120 with the cheeks 124 extending downwardly, as shown in Figs. 1 and 2. Having positioned the hide or skin, the operator presses on the treadle 35, lifting the links 37 and 64 upward, causing an upward movement about 125 130

the pivot point of the levers 38 and 65. The rollers 68 resting on the pockets 80 in the levers 38 and 65 are moved upward to bring the rollers into position to engage with the 5 face 82 on the cam members 69, and during this upward movement the levers 52 are rotated about their pivot point, moving the system of levers and links 52, 57, and 56 from the position shown in Fig. 1 (with respect to the sector 47) and into the position 10 shown in Fig. 4; that is, with the clamp bar 54 clamping the hide or skin 71 firmly at the clamping groove 48, as shown in Fig. 4. Simultaneously with this rotative movement 15 of the lever 52 the lug 40 on lever 38 engages with the upper nuts 42 on the member 41 causing the operation of the clutch mechanism 22 by means of the bell crank lever associated therewith. When the clutch is in 20 operation, the shaft 17 rotates in the direction of the arrow shown in Figs. 2 and 4 and in its rotation carrying the sector 47 in such a manner as to bring the hide or skin into engagement with the cutting blade 91. 25 It has been assumed that power has been transmitted from the fast pulley 32 through the shaft 30 and the system of gearing 29, 28, 25, and 26 to the shaft 21. The rotation of the shaft 30 causes, by means of the 30 bevelled gear 109, bevelled pinion 108, shaft 105, bevelled pinions 103 and 102 a rotation of the shaft 97. The eccentric 99 thereon cooperating with the eccentric strap 100 on the connecting rod 95 causes a reciprocating 35 movement of the slide 85, carrying the knife 91, so that it is obvious that, as the hide or skin 71 is moved past the knife 91, the cutting is performed with a reciprocatory motion. When the shaft 17 is rotated to a point 40 just beyond the position shown in Fig. 4, the roller 68 will have become disengaged with the inner surface of the cam 69 and allowing the operation of breaking the toggle 45 between the members 56 and 57 and moving the system of levers and links (with respect to the sector 47) from the position shown in Fig. 4 to the position shown in Fig. 5. During the rotative movement of the shaft 17, there was wound up on the pulley 50 75 a cord 76 that carries at its free end the weight 79. Simultaneously with the engagement of the lugs 74 with the bolts 73, the one revolution clutch 22 is thrust out of action and for a moment the shaft 17 is 55 brought to rest. When the system of levers and links is moved into position shown in Fig. 5, the hide or skin 71 by its own weight falls off the sector 47 and onto the conveyor belt 117, this belt being rotated from the 60 shaft 97 by means of the chain 115 as above described. The clutch 22 being disengaged from the shaft 17, the weight 79, through the cord 76, rotates the shaft 17 and attached 65 parts in the reverse direction from that above described; that is, in the direction in-

dicated by the arrow in Fig. 5. Referring to Fig. 5, it will be noted that the roller 68 now occupies such a position relative to the cam 69 that, when the shaft 17 rotates in the direction of the arrow shown in such 70 figure, the roller 68 will engage with the upper or outer surface of the cam member 69 and will be brought into the pockets 80 on the levers 38 and 65 preparatory to a further operation. 75

While I have necessarily shown and described the preferred embodiment of my invention somewhat in detail, it is understood that I may vary the size, shape, and arrangement of parts within wide limits without departing from the spirit of the invention. 80

Having thus described my invention, what I claim as new is:

1. An improved cheecking machine, comprising a rotatably mounted shaft, a driving member therefor, a one revolution clutch connecting said shaft with said driving member, a cheecking knife, a hide holding sector operatively associated therewith, means for holding a hide on said sector, locking means for the hide holding means including a stationary cam, and means for releasing the holding means from locked position at a predetermined point in the revolution of the shaft. 90

2. In an improved cheecking machine, the combination of a hide holding sector provided with a cylindrical operating surface, a longitudinal groove formed in said sector on the side thereof opposite said operating surface, a locking bar, pivotally mounted levers at each end of said bar, bell crank levers at each end of the sector, connecting rods extending between each end of the levers and one arm of the bell crank levers, and means for operating the bell crank levers to move the locking bar into locking position with respect to said groove. 100

3. In an improved cheecking machine, the combination of a hide holding sector provided with a cylindrical operating surface, a longitudinal groove formed in said sector on the side thereof opposite said operating surface, a locking bar, pivotally mounted levers at each end of said bar, bell crank levers at each end of the sector, connecting rods extending between each end of the levers and one arm of the bell crank levers, cam rollers mounted on each of said bell crank levers, stationary cam cooperating with said cam rollers, and means for rotating the bell crank levers into position to bring the locking bar into association with the locking groove and the cam rollers into association with the stationary cam whereby the locking bar is maintained in locking position for a predetermined portion of the revolution of the shaft. 110

4. In an improved cheecking machine, the combination of a rotatably mounted shaft, a 120

driving member therefor, a clutch for connecting the driving member and the shaft for rotating the shaft through one revolution, a cheeking cylinder mounted on said shaft, a locking groove in said cylinder, a locking bar associated with said locking groove, means for moving said locking bar into association with the locking groove to hold a hide in position on said cheeking cylinder during a predetermined portion of the revolution of said shaft, means for automatically releasing said locking bar thereafter, a cheeking knife adjustably and slidably mounted in operative association with the cylinder, and means for automatically

controlling the operation of said connecting clutch.

5. An improved cheeking machine, comprising a rotatably mounted shaft, a hide holding sector secured to said shaft and rotatable therewith, a longitudinal groove on said sector, a toggle operated locking device cooperating therewith, and means for automatically holding the hide in clamped position on the sector during the rotation of such sector.

In testimony whereof, I have signed my name to this specification.

DANA E. HARDING.
